DEVICE FOR TREATING WIRE

Lawrence R. Hill, Wilkinsburg, and John J. Keyes, Edgewood, Pa., assignors to Westinghouse Electric Corporation, East Pittsburgh, Pa., a corporation of Pennsylvania

Application April 30, 1945, Serial No. 591,072

5 Claims. (Cl. 91—53)

1

This invention relates to wiping devices for controlling the amount and distribution of coatings applied to the surfaces of wire and the like.

In applying coatings of varnishes, enamels, resins, lubricants, and numerous other coating compositions to wire, it is a desirable feature that the coatings be so applied or treated that they form a relatively uniformly thick film or layer on the wire. While numerous wiping devices to accomplish this result have been proposed in the art heretofore, it has been found that they are not capable of effecting a sufficiently constant and accurate control of the applied coatings. In practice it has been found that most wiping devices available to the art will often wipe one or two sides of a wire almost dry and other sides will carry a greater thickness of coating than is desirable. In some cases, the prior art wiping devices lack adjustability to accommodate ordinary changes in size and shape of the wire being treated. In other cases, the wiping devices are subject to rapid wear without provision being made to accommodate or to compensate for such wear. Therefore, a wiping device would permit progressively thicker or non-uniform coatings to be carried by the wire until it was removed and repaired or rebuilt.

The object of this invention is to provide an improved device for accurately controlling the amount and distribution of coatings applied to wire and the like.

A further object of this invention is to provide a readily adjustable wiping device for accurately controlling the amount and distribution of coatings applied to wire and the like.

A still further object of the invention is to provide a wiping device capable of accommodating a variety of wire shapes and sizes for controlling the amount and distribution of coatings applied thereto.

Other objects of the invention will, in part, be obvious and will, in part, appear hereinafter.

For a fuller understanding of the nature and objects of this invention, reference should be had to the following detailed description in conjunction with the accompanying drawing, in which:

Figure 1 is a vertical cross-section of the wiping device of this invention;

Fig. 2 is a plan view of a portion of the device of Fig. 1;

Fig. 3 is a vertical cross-section through a modified form of the wiping device;

Fig. 4 is a top plan view of the device of Fig. 3; and

Fig. 5 is a perspective view of another modifi-

2

cation of a portion of the wiping device of Figure 3.

Referring to Fig. 1 of the drawing, there is illustrated the improved wiping device 10 embodying our invention enabling a constant and precise control of thickness of coatings of enamels, varnishes, paints, oils, asphalts, and numerous other compositions on wire. The device 10 is shown associated with a wire coating device generally designated as A. The wiping device 10 comprises a housing 12 having a cylindrical chamber 14 therein and provided at its lower end with a closure member 16 for one end of the chamber 14. The closure member 16 is provided with an aperture 18 to permit the passage of wire through the wiping device. The closure member 16 has an enlarged recess 20 coaxial with and adjacent the aperture 18 and a ring-shaped boss 22 closely fitting the walls and projecting into the cylindrical chamber 14. A plurality of machine screws 24 fasten the closure member 16 to the housing 12. The upper end of the housing 12 remote from the closure member 16 has an upper wall 26 provided with cylindrical aperture 28 of a diameter similar to the recess 20. At the upper end of housing 12 a screw thread 30 is provided about the exterior of the housing. A screw-threaded cap member 32 cooperates with the threaded portion 30 of the housing for rotatable engagement therewith. The cap member 32 is provided with a recess 34 in prolongation of the aperture 28 leading to an aperture 36 for passage of wire, the aperture 36 being similar to the aperture 18 in the closure member 16.

A helical spring member 38 constituting the wiping element proper of the device for controlling the amount and thickness of applied coatings on wire is disposed within the chamber 14 and fits within recesses 20 and 34 of the closure member and cap member, respectively. The helices of the spring member 38 are preferably in contact with one another. One end 40 of the helical spring member 38 may extend radially or tangentially into a recess 42 in the closure member 16 whereby that end of the spring member is fixed with respect to the housing. The other end 44 of the helical spring member is disposed within a recess 46 in the rotatable cap member 32 for rotation therewith. It is necessary that the pitch of the thread 30 be substantially the same as the diameter of the wire, or longitudinal dimension if non-circular wire be used for the helical spring member, forming the member 38 for reasons that will be apparent here-

inafter. The upper face of the housing 12 carries a plurality of spaced recesses 48 best shown in Fig. 2. The rotatable cap member 32 is provided with a single through opening 50 capable of being aligned with any one of the recesses 48. A latch means 52 is provided for passage through the opening 50 and into the recesses 48 for locking the rotatable member 32 in any selected position of rotatable adjustment.

A resilient packing 54 is provided within the chamber 14 between the helical spring member 38 and the housing 12. The packing 54 may be composed of rubber, either natural rubber or a synthetic rubber or elastomer, such, for example, as polychlorbutadiene polymers, polyisobutylene, or butadiene-styrene copolymers, polyvinyl alcohol, polysulfides, and the like, or felt. The rubber or other resilient elastomeric packing selected will depend upon the chemicals applied to the wire or the nature of the solvent present therein. The resilient packing 54 may be spongy or cellular to provide for sufficient expansion without undue pressure.

The main function of the resilient packing 54 is to prevent wiped off coating material from working up to the top of the device 10 and redepositing on the wire or gumming up the outside of the device 10. The packing also provides for centering the resilient spring member 38 by preventing buckling or distortion thereof during use. The resilient packing also prevents accumulation of paint or varnish or other coating composition in the chamber 14 which would give rise to difficulty if such accumulation hardened.

In order to compress the resilient packing tightly about the spring member 38 after it has been introduced into the chamber 14, the closure member 16 is provided with a boss 22. In some cases it may be desirable to provide an adjustable compressing means for applying more or less compression to the resilient packing 54. A threaded machine screw passing through the closure 16 and projecting partly into the chamber 14 can be employed for this purpose or the boss 22 may be a movable ring adjustable by such machine screw. Alternatively a removable shim member between closure 16 and housing 12 will permit variable movement of boss 22 into chamber 14.

In treating wire with applied coatings thereon, the helical spring member 38 is selected with an internal diameter slightly larger than the desired diameter of the wire and applied coating. As shown in Fig. 1, the wire 60 after passing through the coating device A consisting, for example, of an enamelling pan 62 containing an enamel or varnish 64 is directed upwardly to the wiping device 10. The wire 60 passes through the aperture 18 into the interior of the helical spring member 38 where it is wiped to a predetermined coating thickness and passes out through aperture 36. In order to adjust the helical spring members to a selected internal diameter, the pin 52 is lifted to permit the rotatable cap 32 to be turned on threads 30 and rotated to wind up the spring member to decrease the diameter or to unwind the spring to increase the diameter. The thread 30 is such that the cap 32 tends to move away from the housing as the spring member 38 is contracted on rotation of the cap counterclockwise, as seen in Fig. 2. This relative outward movement of cap 32 accommodates the elongation of the spring 32 on contracting movement thereof and the inward move-

ment of the cap corresponds to the shortening of the spring on reverse rotation of cap 32.

When turned counterclockwise, as shown in Fig. 2, the helical spring member 38 is wound tighter, acquiring one extra turn for each revolution of the cap 32. This causes a small and accurately controllable decrease of the internal diameter of the helical spring member. The rotatable cap member can thus be rotated until the internal diameter of the helical spring member wipes the coating on the wire 60 to the precise thickness required. When the closure cap 32 has been rotated to the precise position required, the pin 52 is inserted within the opening 50 and into one of the recesses 48. By means of this adjustment, a very close control of the final diameter of the coating on the wire 60 can be attained. If the helical spring member wears slightly after prolonged use, the cap member 32 can be set to another position to accommodate such wear.

The helical spring member can be made of any suitable material desired. Ordinary carbon steel piano wire has been found satisfactory for most practical purposes. Alloy spring steels such as nickel-chrome-molybdenum steels and the like, can be employed if resistance to acids and other corrosive materials is required. In some cases Phosphor bronze or copper alloyed with beryllium and other metals may be used for the helical spring member. Obviously the helical spring member 38 need not be made of round wire but may be made of square wire, flat strip, or of any other selected cross-sectional shape wire.

The wiping device 10 is customarily employed in position shown in Fig. 1 whereby the excess amount of coating wiped off the wire 60 runs back into the pan 62. However, the wiping device can be employed in a horizontal position or in any other position required in use.

The device of Figs. 1 and 2 has enabled the most satisfactory control of the amount and distribution of coatings on wire of any device known or used in the art at the present time. Tests show that all sides of wire wiped with the device carried very closely the same thickness of coating after passing through the helical spring member. The helical arrangement appears to facilitate and improve the coating distribution. The thickness of coatings is readily controllable within a fraction of a thousandth of an inch. This feature is particularly important in wire enamelling. Furthermore, the adjustment of the wiping device once obtained has been found to remain sufficiently precise even after a prolonged period of use. For example, the wear on the helical spring member has been found to be negligible in wire enamelling use even after several months continuous usage.

The helical spring member of Fig. 1 obviously is limited to the treatment of circular wire within a limited range of diameters for a given diameter helical spring 38. For treating wire of other cross-sectional shapes, such, for example, as square wire, hexagonal wire, flat strips, and the like, a modified form of the wiping device 10 is employed as shown in Figs. 3 and 4 of the drawing. The device 10 consists of a housing 72 provided with a cylindrical chamber 74 and carries a closure member 76 fixed at the low end thereof by machine screws 82. The closure member 76 is provided with a relatively large aperture 78 for accommodating the passage of wire up to a large size and of a variety of shapes. A boss 80 on the closure member is provided for maintaining a helical spring member 96 in predetermined posi-

tion, as will be explained in detail subsequently. The upper end of the housing 72 opposite the closure 76 is provided with an external screw thread 84 cooperating with the screw-threaded rotatable cap member 86. An enlarged threaded aperture 88 in the cap member 86 carries a threaded centering member 90 provided with a wire outlet aperture 92 of a diameter corresponding to that of the aperture 78 and aligned therewith. The centering member 90 is fitted with a projecting boss 94 of a slightly lesser diameter than that of the chamber 74 to fit within and to maintain the helical spring member 96 in position. The helical spring member 96 has one end 98 fixed within the lower end of the housing 72 while the other end 100 of the helical spring member projects into a channel 102 within the rotatable cap member 86. An open slot 104 in the side of the cap member 86 permits the passage therethrough of a latching pin 106 capable of fitting into any one of a number of apertures 108 drilled into the outer circumference of the housing 72 for the purpose of locking the cap member 86 in any predetermined position.

The helical spring member 96 will fit against the wall of the chamber 74 at one extreme position, and by rotating the cap member 86 counterclockwise as seen in Fig. 4, the helical spring member 96 will become smaller in internal diameter. By reason of the contraction in diameter the ends 98 and 100 of the spring would tend to emerge from the recesses in which they are lodged were it not for the bosses 80 and 94 which constrain the end turns of the helical spring member 96. The bosses 80 and 94 further center the helical spring member 96 with respect to apertures 78 and 92.

Disposed within the interior of the helical spring member is a flexible packing 110 provided with a predetermined sized channel 112 for accommodating the passage of wire having coatings thereon. The resilient packing 110 may be prepared from various flexible resins, elastomers or rubbers, both natural and synthetic, or felted products selected as described with respect to the packing 54. A sponge rubber such as polysulfide elastomer has been found to be satisfactory for the packing 110 though the rubber or elastomer may have any other predetermined physical structure to give a predetermined resiliency or hardness, depending on the requirements of the application.

By removing the pin 106 and rotating the closure member 86, the helical spring member 96 may be contracted in diameter, thereby compressing the resilient packing 110 and applying more pressure to a wire passing through the wiping device 70 and thus suitably dimensioning the thickness of the applied coating which will be present on the wire. The screw threads 84 should be of a pitch closely corresponding to the diameter of the wire forming helical spring member 96 in order to accommodate the resulting changes in length of the spring member.

It will be obvious that other latching means than the pin type devices shown can be employed. A spring plunger similar to those often used on window sash, for example, may be employed. Again the pins may be replaced by machine screws and thus be fixed more securely in threaded apertures 48 or 108.

The device shown in Figs. 3 and 4 will accommodate a variety of sizes and shapes of wire carrying a variety of applied coatings. The wiping device of Figs. 3 and 4 is particularly satisfac-

tory for wiping wire carrying a fibrous covering, such, for example, as asbestos, cotton, glass fiber, both continuous filament and sliver, and similar wrappings thereon, which wrappings are treated with a varnish or enamel or other composition to provide for predetermined insulation properties.

Due to the fact that the wiping device of Figs. 3 and 4 may impose greater pressures on the corners than the flat sides of square wire or wire of polygonal shape, or even flat wire, it may be desirable to employ the internal modification shown in Fig. 5 in the device of Fig. 3. As illustrated in Fig. 5, disposed within the helical spring member 96 is a resilient member 120 preformed or molded to a square external shape and provided with a square aperture 122 closely dimensioned to the dimensions of the wire to be wiped thereby. The square resilient member 120 is fitted with segmental members 124 somewhat smaller across the chord than its sides on each side for applying a uniform pressure thereto as the helical spring member 96 varies its dimensions. It will be apparent that a corresponding polygonal construction of resilient members and segmental members may be made to accommodate almost any predetermined shape of wire. The segments 124 permit the uniform converging of the four sides of the aperture 122 to provide the required thickness of coating on all of a square wire passing therethrough. It will be obvious that this modification of the invention will permit the coating to be uniformly applied over the entire surface of a wire regardless of its shape, and corners in particular will not be wiped excessively.

The term "wire" as employed herein refers to elongated strips of any material such as metal, glass, resin, or the like of any predetermined cross-sectional shape, such as round, square, hexagonal, rectangular, and the like. We have been able to treat copper wire with the wiping devices of this invention from sizes as small as about size 22 to as much as $\frac{1}{4}$ inch rectangular and flat strip.

The wiping devices have been effective with both hot and cold coatings such as enamels over a wide range of viscosities. The thickness of coatings has been precisely controlled where the range of viscosity of the applied materials has been from the order of that of water to as thick and heavy as molasses.

Since certain changes in carrying out the above invention and certain modifications in the apparatus which embody the invention may be made, without departing from its scope, it is intended that all the matter contained in the above description or shown in the accompanying drawing shall be interpreted as illustrative and not in a limiting sense.

We claim as our invention:

1. In a wiping device for controlling the amount and distribution of coatings applied to wire comprising a housing having a chamber therein, a helical spring member disposed in the chamber in the housing, one end of the helical member being fixed to the housing, an adjustable member fitted to the housing for rotatable motion with respect to the housing, the other end of the helical member being attached to the adjustable member whereby the internal diameter of the helical member may be varied by rotating the adjustable member with respect to the housing, an elastomeric packing associated in pressure contact with the helical member to promote accurate wiping of the applied coatings, and aper-

tures in the housing aligned with the helical member for passage of wire therethrough.

2. In a wiping device for controlling the amount and thickness of coatings applied to wire comprising a housing having a chamber therein, an aperture at one end of the housing leading to the chamber, the housing having a screw-threaded portion at a point opposite the location of the aperture, a helical spring member disposed in the chamber, one end of the helical spring member being fixed to the housing at a point adjacent the aperture, a threaded member engaging the threaded portion of the housing, the threaded member having an aperture, the other end of the helical spring member being fixed to the threaded member, the pitch of the threads being substantially equal to the longitudinal dimension of each helix of the helical spring member whereby when the threaded member is rotated said other end of the helical spring member is likewise rotated and the diameter of the helical spring member is varied without substantial variation in distance between helices, the apertures in the housing and threaded member being aligned with the interior of the helical spring member for passage of wire therethrough, and locking means to hold the threaded member in any selected position.

3. In a wiping device for controlling the amount and thickness of coatings applied to wire comprising a housing having a chamber therein, an aperture at one end of the housing leading to the chamber, the housing having a screw-threaded portion at a point opposite the location of the aperture, a helical spring member disposed in the chamber, one end of the helical spring member being fixed to the housing at a point adjacent the aperture, a threaded member engaging the threaded portion of the housing, the threaded member having an aperture, the other end of the helical spring member being fixed to the threaded member, the pitch of the threads being substantially equal to the longitudinal dimension of each helix of the helical spring member whereby when the threaded member is rotated said other end of the helical spring member is likewise rotated and the diameter of the helical spring member is varied without substantial variation in distance between helices, the apertures in the housing and threaded member being aligned with the interior of the helical spring member for passage of wire therethrough, locking means to hold the threaded member in any selected position, and a resilient packing between the walls of the chamber and the helical spring member to prevent leakage of wiped off coating material and to prevent buckling or other misalignment of the helical spring member.

4. In a wiping device for controlling the amount and thickness of coatings applied to wire comprising a housing having a chamber therein, an aperture at one end of the housing leading to the chamber, the housing having a screw-threaded portion at a point opposite the location of the aperture, a helical spring member disposed in the chamber, one end of the helical spring member being fixed to the housing at a point adjacent

cent the aperture, a threaded member engaging the threaded portion of the housing, the threaded member having an aperture, the other end of the helical spring member being fixed to the threaded member, the pitch of the threads being substantially equal to the longitudinal dimension of each helix of the helical spring member whereby when the threaded member is rotated said other end of the helical spring member is likewise rotated and the diameter of the helical spring member is varied without substantial variation in distance between helices, the apertures in the housing and threaded member being aligned with the interior of the helical spring member for passage of wire therethrough, locking means to hold the threaded member in any selected position, and a resilient packing disposed within the helical spring member, the packing having a longitudinal passage in line with the apertures, the coated wire passing through the longitudinal passage.

5. In a wiping device for controlling the amount and thickness of coatings applied to wire comprising a housing having a chamber therein, an aperture at one end of the housing leading to the chamber, the housing having a screw-threaded portion at a point opposite the location of the aperture, a helical spring member disposed in the chamber, one end of the helical spring member being fixed to the housing at a point adjacent the aperture, a threaded member engaging the threaded portion of the housing, the threaded member having an aperture, the other end of the helical spring member being fixed to the threaded member, the pitch of the threads being substantially equal to the longitudinal dimension of each helix of the helical spring member whereby when the threaded member is rotated said other end of the helical spring member is likewise rotated and the diameter of the helical spring member is varied without substantial variation in distance between helices, the apertures in the housing and threaded member being aligned with the interior of the helical spring member for passage of wire therethrough, locking means to hold the threaded member in any selected position, a resilient packing disposed within the helical spring member, the packing having a longitudinal passage of polygonal cross-section in line with the apertures, and a plurality of segmental members disposed between the resilient packing and helical spring member to maintain the polygonal cross-section as the helical spring member is varied in diameter.
